TREATMENT OF HYDROCARBON OILS

Gustav Egloff, Chicago, Ill., assignor to Universal
Oil Products Company, Chicago, Ill., a corpora-
tion of South Dakota

Application February 10, 1930, Serial No. 427,126

2 Claims. (Cl. 196—62)

This invention relates to a process for the treatment of hydrocarbon oils and refers more particularly to a process for the hydrogenation of oils at elevated temperatures.

- 5 Among the objects of the process is to increase the yield of the lower boiling products made by the thermal decomposition or cracking of higher boiling oils; to saturate in part the more highly unsaturated hydrocarbons, especially those which 10 form gums, polymers and other undesirable materials in the motor fuel product; and to desulphurize in part the hydrocarbons to render them more suitable for motor fuel and to facilitate and reduce the cost of refining.
- 15 It is not the purpose of this invention necessarily to completely saturate the hydrocarbons of the olefin series to produce paraffin hydrocarbons, but rather to add hydrogen in regulated amounts to the more highly unsaturated hydrocarbons for 20 the aforementioned purposes.

In the present invention, the hydrocarbons are treated in the vapor state. Gasoline, which is the major product of the cracking process, contains highly unsaturated hydrocarbons which upon standing polymerize and oxidize to form gums, tars, and other undesirable substances. The presence of sulphur compounds in a motor fuel may result in destructive corrosion of the crank case and other parts of the motor during combustion 30 and may also result in the destructive corrosion of the cracking or distillation equipment.

Among the objects of my invention is the minimizing of these objectionable features.

In the specific embodiment of my invention, the 35 oil in a vapor state is mixed with a metallic hydride or mixture of hydrides made by heating metals of the alkali or alkaline earth series such as sodium, potassium, calcium, barium, strontium, magnesium, etc., with hydrogen. The mixture of 40 oil and hydride is subjected to treatment with steam at an elevated temperature, the hydride reacts with the steam forming hydrogen and the corresponding oxides of metals which may have a catalytic effect in the reaction including the 45 hydrogenation, desulphurization and the conversion or cracking.

In the operation of the process of my invention, the hydrides preferably in a finely divided state are introduced simultaneously with steam in those 50 portions of the cracking system where the oil is in the vapor state—e. g., in the reaction chamber and dephlegmator and vapor lines or enlarged portion thereof. The steam reacts with the finely divided hydrides forming hydrogen in situ. The 55 newly liberated hydrogen, which is more active than ordinary molecular hydrogen and is sometimes spoken of as being in the nascent state, reacts with the chemically unsaturated portions of the oil vapors as well as with sulphur compounds, saturating in part the olefinic hydrocar- 60 bons and reducing some of the sulphur compounds to hydrogen sulphide which may readily be removed from the final products.

As further examples of hydrides, I may use those of sodium, potassium, calcium, magnesium, 65 zinc, aluminum, iron, tin and others, including alloys and amalgams preferably the metals which are electro-positive to hydrogen and which liberate hydrogen from steam. The corresponding oxides of the metals formed by the reaction with 70 steam have some catalytic reaction in promoting the hydrogenation and desulphurization reaction as well as assisting in the cracking reaction. The use of finely divided hydrides has an additional 75 advantage in that the finer the hydride the greater the surface exposure and consequently the greater the velocity or rate of reaction.

In addition to the above I may also add molecular hydrogen to the materials undergoing reaction in order to assist in the reaction, or 80 I may add gases containing hydrogen such as gases from oil cracking, coke oven gas, producer gas, natural gas, etc.

The herein described process of my invention may be carried out in any conventional or desirable type of process for cracking hydrocarbon oil. The attached drawing is a diagrammatic illustration in side elevation of one form of conventional cracking process wherein my invention is adaptable. In this drawing raw oil charging 85 stock for the process may be passed from a source of supply through a line 1, controlled by a valve 2, by means of a pump 3 and via line 4 to a heating coil 5 wherein said oil is subjected to the desired conversion temperature and pressure. 90 The highly heated oil from the coil 5 may then be passed via transfer line 6, controlled by valve 7, to an enlarged reaction zone 8, wherein further conversion of the oil may take place, and wherein the liquid and vaporous products of reaction 95 100 separate. The heavy, unvaporized residual products produced within the reaction zone 8 may be discharged from the system through a line 9, controlled by a valve 10, while the lighter, vaporous products of reaction may be discharged from 105 said zone through a line 11, controlled by a valve 12 into a suitable fractionating zone 13 wherein separation of the lighter from the heavier components of said vapors occurs. The 110 separated and condensed, insufficiently converted

- components of the vapors undergoing fractionation within said zone 13 may be returned to the heating coil 5 for further conversion through a line 14 leading from said fractionating zone to the pump 3 which communicates with the line 4 leading to said heating coil. The lighter, sufficiently converted fractions produced in said fractionating zone may be passed via line 15, controlled by valve 16, to a suitable condenser 17, from whence the liquefied product passes to a receiver 19, passage from said condenser to said receiver being controlled by a suitable valve 18. The incondensable gases produced in the system and collecting in the receiver 19 may be discharged from the latter through a suitably valved line 20, while the distillate collecting in said receiver may be withdrawn therefrom to suitable storage through a valved line 21.
- Metallic hydrides for utilization in the process may be introduced, together with desired quantities of steam, either into the reaction zone 8 or into the fractionating zone 13, or to both said reaction zone and said fractionating zone, whereby said hydrides may react with the hydrocarbons under treatment in either or both of said zones. For example, any suitable hydride, preferably while in finely divided form may be introduced into the reaction zone 8 from a source of supply (not shown) through a line 22, controlled by valve 23, while steam may be introduced into said zone in regulated quantities from a convenient source (not shown) through a line 24, controlled by a valve 25. Likewise, any suitable hydride while preferably in finely divided form may be introduced into the fractionating zone 13 through a line 26, controlled by a valve 27, together with regulated quantities of steam through a line 28, controlled by a valve 29.
- Preferably the oil is heated to a cracking temperature, although my invention contemplates operating the process at lower temperatures also. Preferably the process is operated at atmospheric pressure or at super-atmospheric pressure, and may in some cases also be operated at atmospheric or reduced or sub-atmospheric pressures. Generally I make use of super-atmospheric pressures ranging from 75 pounds to 3000 pounds, more or less, and at temperatures of from approximately 400 degrees to 1400 degrees F.
- As an example of the results obtained by the process, a 27° Baumé gravity Mid-Continent topped crude when subjected to a cracking tem-

perature of approximately 920 degrees F., and a pressure of approximately 1000 pounds using approximately 10% by weight of the hydride of sodium and 10% by weight of steam based on the oil charged, shows an approximate yield of 80 gasoline of sixty percent, in addition to approximately fifteen percent of pressure distillate bottoms or gas oil which may be utilized as recycle stock. Coke and gas are also valuable products of the process. The sulphur content of the gasoline produced, which would normally be approximately 0.3 percent, may be reduced to approximately 0.1 percent.

The above example is purely illustrative and is not to be construed as a limitation of the broad scope of the invention.

I claim as my invention:

1. A process for hydrogenating hydrocarbon oil, comprising subjecting said oil to conversion conditions of temperature and pressure in a heating zone, passing the resultant products from said heating zone into a reaction zone wherein further conversion occurs, introducing the lighter products of reaction into a fractionating zone wherein the lighter, sufficiently converted fractions separate from the heavier, insufficiently converted fractions, the improvement which comprises introducing metallic hydrides and steam into the vapors undergoing treatment in said reaction zone and fractionating zone to effect 105 a liberation of nascent hydrogen and a saturation of said vapors.

2. A process for hydrogenating hydrocarbon oil, comprising subjecting said oil to cracking temperatures and pressures in a heating zone, introducing the highly heated products from said heating zone into an enlarged reaction zone wherein further conversion occurs and liquids and vapors separate, the liquid being withdrawn from the process, passing the vaporous products of reaction into a fractionating zone for separation of its lighter from its heavier constituents, the latter being returned to the heating zone, introducing metallic hydrides and steam into the vapors undergoing treatment in said reaction and fractionating zones for generation 120 of nascent hydrogen therein, and maintaining hydrogenation conditions of temperature and pressure in each of said reaction and fractionating zones.
